No. 1342

John Polhamus, of New York, N.Y.
Letters Patent No. 1342. Dated Nov. 13th 1860.

The schedule referred to in these Letters Patent and making part of the same.
To all whom it may concern:

Be it known that I, John Polhamus, of the City and State of New York, have invented and made a new and original Ornamental Design for the handles of Spoons, Forks, and articles of Table Cutlery; and I do hereby declare that the following is an accurate description thereof, reference being had to the annexed drawing making part of this specification, wherein,

Fig. 1. is an elevation of my said design as applied to a spoon; and

Des. 1342

Fig. 2, is the portion of the design at the junction of the handle and bowl:

The character of this ornamental design will be apparent from the drawing. The design consists of raised work to be struck up on the metallic surface by dies. The design to be embossed near the end of the handle is a series of egg-shaped ornaments, and at the end of the handle is a leaf shaped ornament and also near the small part of the handle and at the junction with the spoon, bowl, or fork, as represented in Figs 1 and 2, I form embossed leaflets.

The edges of the handle are formed with plain grooves and beads.

What I claim and desire to secure by Letters Patent is the ornamental design to be struck up or embossed upon the handles of spoon, fork, or other articles of table cutlery as represented in the drawing and set forth herein.

In Witness whereof, I have hereunto set my signature
this Twenty Eighth day of September, 1860.

Witnesses:

Samuel W. Ferrell, *S*
